Company, Portland, Oreg., a corporation of
Oregon

Application August 29, 1950, Serial No. 181,982

2 Claims. (Cl. 20—93)

1

This invention relates to a new and improved form of patch for repairing defects in plywood, veneer, lumber, and the like.

It has long been the custom to improve the grade of wood by routing out small knots, pitch pockets, checks and such defects, to form a shallow recess of some standard size and shape, and then fitting in a thin patch of clear grained wood veneer to cover the underlying defect. Various forms of patches have heretofore been devised for this purpose. For the most part, such patches have been circular, boat-shaped or elongated patches with rounded ends, all of which have a number of disadvantages. They are wasteful of the high grade patch veneer, they are not well suited for rapid production in quantity, they are not conveniently adaptable to the patching of defects of different sizes, and they leave much to be desired in the quality of the bond obtained at the end grain edges of the patch.

Objects of the present invention are, therefore, to provide a better form of patch which overcomes the shortcomings and disadvantages of prior known patches, particularly with respect to reducing waste of the patching veneer, simplifying and accelerating the production of the patches, facilitating the application of patches of different sizes and improving the glued joint at the edges of the patch.

The present patch is referred to as a sled patch because it is rectangular in outline and has a bottom surface which slopes upwardly at the ends of the patch like the front of a sled or toboggan. This form of repair enables the patches to be made in strip form for convenient handling, and utilizes the high grade patching veneer with very little waste. The patches may be machine made to different lengths without involving more than simple adjustments in the patch cutting machine and the defect routing machine, using the same strip stock and the same heat and pressure applicator for setting patches of different size. Some of the most common defects in wood, such as checks and pitch seams, are relatively narrow but may run a considerable distance with the grain, with the result that there is considerably more need for a long patch than there is for an abnormally wide patch. Heretofore, long defects have been repaired by applying a series of short patches in overlapping, end to end relation, involving duplication of effort, and making the patches quite conspicuous where they intersect each other. By the use of the present patch, a single long patch will usually repair such defects in one operation. The most noticeable parts of a patch re-

2

pair are its ends, the side joints being relatively inconspicuous, and so a long defect can be repaired even more inconspicuously with the present type of patch than a short defect because the two ends of the patch are farther apart.

The present sled patch also effects a marked improvement in the bond at the end of the patch by substantially eliminating end grain in the joint. Glue bonds between wood surfaces are 10 the weakest in end grain joints, and the end grain joints reach their maximum peripheral extent in the circular and rounded end patches heretofore used. In such patches, the bonds at the end grain surfaces are relatively ineffective, and the 15 principle edge bond is limited to the short extent of edge grain surfaces, which are a minimum in circular patches. In the present patch, the sloping sled ends cut across the grain at a relatively flat angle so that a flat grain joint is obtained, 20 in effect, to the very ends of the patch. This is particularly important in the patching of single sheets of veneer where the patch can be secured only at its edge surfaces.

In the repair of plywood, the sloping ends of 25 the sled patch are bonded securely to the top or face veneer, in addition to the bond between the under surface of the patch and the core veneer of the panel. Circular and boat-shaped patches are deficient in edge grain joint surfaces, 30 but the present sled patch has edge grain bonds extending the full length of the patch. Thus, the present patch is not merely stuck in its prepared opening with sufficient adhesion to hold it in place, but is bonded securely in the 35 edge joint around its entire perimeter with the veneer from which the defect was removed, regardless of whether the patch is in a single sheet of veneer or the face veneer of a multi-ply panel.

Other objects and advantages will become apparent and the invention will be better understood with reference to the following description of a preferred embodiment of the invention illustrated on the accompanying drawing, but it is to be understood that the drawing is intended 45 for the purpose of illustrating the principles of the invention and is not intended to limit the invention.

In the drawing:

Figure 1 is a perspective view of a sled patch; 50 Figure 2 is a cross sectional view taken on the line 2—2 of Figure 1;

Figure 3 is a longitudinal sectional view taken on the line 3—3 of Figure 1;

Figure 4 is a perspective view of a strip of sled patches;

Figure 5 is a perspective view, with parts in

section, showing the present patch installed in a plywood panel;

Figure 6 is a perspective view, with parts shown in section, to illustrate the application of the present patch to a single sheet of veneer;

Figure 7 is a diagram illustrating the relatively flat angle of the sloping edge surfaces in the end joints;

Figure 8 illustrates the first step in a preferred method of making the present patch;

Figure 9 is a sectional view taken on the line 9—9 of Figure 8; and

Figure 10 illustrates another step in the making of the patches.

In Figures 1, 2 and 3 the patch P is rectangular in outline, having a top surface 10, a bottom surface 11 having longitudinal flat grain, sloping side grain edges 12, and curved, sled-shaped end joint edge surfaces 13 terminating at the lines 14. The curvature of the sled ends 13 is such that near the bottom surface 11 the grain has flat grain characteristics, and near the top surface 10 it is still predominantly flat grain but has a relatively small component of end grain. No surface on the patch presents a major component of end grain.

The patches are preferably made in strips having a series of patches joined together at break lines 14a to present a continuous, flat, top surface. Figure 4 shows the underside of such a strip 20.

In patching plywood as shown in Figure 5, the patch veneer is usually made of the same thickness as the face veneer 15 of the panel. The thickness of the core veneer 16 is ordinarily greater than that of the face veneer, but the relative dimensions of core and face veneers are immaterial to the patching operation. The panel is prepared by routing out the defect in the face veneer down to the glue line 17 to leave a recess of substantially the same shape and dimensions as the patch P. Thus, the routed recess has longitudinally parallel, inwardly sloping sides substantially to fit the edges 12 of the patch, and curved sloping ends tangent to the glue line 17. The patch P is glue coated on its bottom and end surfaces 11 and 13 with sufficient spread to cause glue to be squeezed up on the edge grain surfaces 12 when the patch is pressed into the prepared opening.

In practice, the recess is cut by a rotary routing tool on a horizontal axis parallel with the work surface, the tool having cutting blades with tapered side edges corresponding to the inclination of side edges 12 of the patch, as illustrated in our copending application, Serial No. 182,285, filed August 30, 1950. Hence, the side edges of the recess on the top surface of the work piece are not parallel at the ends of the recess but converge slightly at the corners 18 of the recess, causing the very ends of the patch to be compressed to some extent in a lateral or transverse direction when the patch is pressed into the recess. This is advantageous as it insures a tight fit at the ends of the patch. The original square corners of the patch P are indicated by phantom lines in Figures 5 and 6.

This sled type of patch is particularly advantageous for plywood and lumber when the glue is cured and set by high frequency dielectric heating applied only to the top side of the work. A pressure member, not shown, having electrodes for dielectric heating is pressed down on the top surface of the patch and energized to produce a direct field across the top surface of the patch

and stray field heating in the continuous glue line on surfaces 11, 12 and 13, without any electrode under the work. The long sweeping curves of the end surfaces 13 bend up to the plane of the direct electrostatic field at the ends of the patch whereby the entire glue line is brought substantially into the direct field and the heating is much more effective than in the usual case of stray field heating where the glue line is electrically isolated from the direct field. Strong edge grain bonds are effected along the edges 12, and a strong flat grain bond is obtained on the bottom surface 11. The sloping end surfaces 13 have predominantly flat grain characteristics and have large joint areas relative to the thickness of the patch. Thus, the ends 13, as well as the edges 12, are bonded securely to unite the perimeter of the patch integrally with the face veneer 15, in addition to the bottom bond at 11.

Figure 6 illustrates how the improved bond obtained at the ends of a sled-shaped patch strengthens the repair of a single veneer where there can be no bond on the bottom face 11. With reference also to Figure 7, it will be seen that if the radius of curvature of the circular arc 30 is made large in relation to the thickness of the veneer, the grain on the surface 13 will be predominantly flat grain and the arcuate length of surface 13 will greatly exceed the thickness of the veneer to provide a large joint area. The arc 30 has its center at 31, and the point 32 is spaced 45 degrees from the point of tangency 33 with the bottom surface 11. As long as point 32 lies above the surface of the patch, the flat grain component in all parts of surface 13 exceeds the end grain component, and so the grain characteristic in surface 13 is said to be predominantly flat grain.

A two-inch radius is appropriate for the arc 30 in commercial thickness of veneer, but this dimension is not critical and the invention is not to be limited by the mention of a specific value. With a two-inch radius in $\frac{3}{2}$ " thick veneer, for example, the arcuate length of surface 13 greatly exceeds the veneer thickness and the maximum end grain component, at point 14, is quite small. By way of contrast, in conventional patches the width of the joint surface is only negligibly greater than the veneer thickness, and a large part of this small bonding surface comprises predominantly end grain. Figure 7 is drawn to scale to illustrate accurately the actual curve of surface 13 in $\frac{3}{2}$ " veneer when the radius of arc 30 is two inches. It is apparent that there is wide latitude in the veneer thickness and arc radius without causing point 14 to approach closely to point 32.

It is preferred to make the present sled patch by first cutting a piece of patch veneer V into a plurality of patch strips 20 having the desired width of the patches, as shown in Figure 8. This is done by cutting parallel tapered slots 21 to make the desired width of faces 10 and 11 and the desired inclination on the edge grain surfaces 12. The only waste in cutting these strips comprises the material removed from the slots 21 and the side trimmings 22.

The strips 20 are then grooved transversely at intervals to form the sled-shaped end surfaces 13. In forming these sled ends, the patches may be severed from the strips, if desired, but, preferably, a thin web of connecting material 14a is left on the face 10, so that the completed patches may still be handled in strip form. In Figure 10, three such shaping operations have been per-

formed on a patch strip, leaving the webs 14a to form break lines by which the patches may be broken apart as they are needed. Additional shaping operations will convert the remainder of the strip into patches all connected together in end to end relation. The only waste in the shaping operation comprises the material removed in cutting the transverse grooves to form the surfaces 13, and the small end pieces 26. Obviously, the patches may be made in a variety of different lengths, as needed, to cover the lengths of the defects to be repaired, so that it will not be necessary to overlap the patches on a single defect, as has been the conventional practice.

By leaving the patches connected together at 14a, a ragged feather edge is avoided at the ends 14, and the ends do not tend to split or splinter. The patches may be handled in strip form, if desired, until they are ready for use, piles of strips of different length patches being made available to the patcher. Upon breaking the patches apart at the lines 14a, clean-cut square ends 14 result. The web portions at 14a may be left very thin, so that after the patches are broken apart there will be no apparent thickness at the ends. In any event, the usual sanding operation makes the top of the patch smooth with the face veneer.

In setting a long patch, the pressure and heat applicator may be moved along the patch in repeated applications to set patches of any length. The patch becomes less conspicuous as the ends 14 become farther apart. Since the patches are of uniform width, the routing tool used for removing the defect, and the pressure and heat applicator, do not have to be changed for patches of different size. Long and short patches may be applied one after another without any interruption in the work.

Having now described our invention and in what manner the same may be used, what we claim as new and desire to protect by Letters Patent is:

- 5 1. A repaired veneer having an opening fitted with a rectangular sled-shaped patch, said opening and patch having flat, downwardly converging, sloping side walls and cylindrical surface end walls tangent to the bottom surface of the veneer and patch, said end walls having uniform predetermined width and an arcuate length considerably less than 45°, the side edges of said opening in the top surface of the veneer converging at their ends to said predetermined width and holding the ends of the patch under transverse compression.
- 10 2. A plywood panel patched by a rectangular sled-shaped patch, said panel having a sled-shaped recess in its face veneer and said patch and recess having flat, downwardly converging, sloping side walls and cylindrical surface end walls, the bottom of the recess including said end walls being of uniform predetermined width and the side edges of the recess on the surface of the wood converging at their ends to said predetermined width and holding the ends of the patch under transverse compression, said end walls being tangent to the bottom of the recess and having an arcuate length considerably less than 45°.
